UNITED STATES PATENT OFFICE

173,130

CARVING AID FORK

Joseph Schoenfeld, San Jose, Calif.

Application March 22, 1954, Serial No. 29,627

Term of patent 14 years

(Cl. D44—29)

To all whom it may concern:

Be it known that I, Joseph Schoenfeld, a citizen of the United States and a resident of San Jose, county of Santa Clara, State of California, have invented a new, original, and ornamental Design for a Carving Aid Fork, of which the following is a specification, reference being had to the accompanying drawing, forming a part thereof.

Figure 1 is a top plan view of a carving aid fork, showing my new design;

Figure 2 is a side elevational view thereof; and

Figure 3 is a front elevational view thereof.

I claim:

The ornamental design for a carving aid fork, as shown.
